UNITED STATES PATENT OFFICE.

HENRY JOHN SCHMID, OF PHILADELPHIA, PENNSYLVANIA, ASSIGNOR TO WILLIAM M. SCOTT, OF TREDYFFRIN TOWNSHIP, PENNSYLVANIA.

SHOCK-PROOF CIRCUIT-BREAKER.

1,355,511.

Specification of Letters Patent.

Patented Oct. 12, 1920.

Application filed October 28, 1919. Serial No. 333,932.

To all whom it may concern:

Be it known that I, HENRY JOHN SCHMID, a citizen of the United States, residing at Philadelphia, in the county of Philadelphia and State of Pennsylvania, have invented certain new and useful Shock-Proof Circuit-Breakers, of which the following is a specification.

My invention relates to an electric switch 10 or circuit breaker which is held in closed position by locking mechanism which may be released by automatic means or otherwise.

It is the object of my invention to provide switch or circuit breaker structure 15 which shall withstand shocks or jars occasioned by forces acting upon the structure in or from various directions, without premature or undesired release of the restraining or locking mechanism.

My invention resides in switch or circuit breaker structure of the character referred to wherein the locking or restraining mechanism comprises a main lock or latch with 25 which co-acts an auxiliary lock or latch to prevent release of the movable member of the switch or circuit breaker upon occurrence of shocks or jars, the auxiliary and main latches or locks being actuated in succession, the auxiliary lock or latch being first actuated and the main lock or latch actuated by or through the auxiliary latch.

My invention resides further in shock 35 proof switch or circuit breaker structure wherein the auxiliary latch or lock is pivoted upon the main lock or latch, which latter is preferably pivoted.

My invention resides in further features 40 of structure and combination hereinafter described and claimed.

I have preferred to illustrate my invention by but one form, selecting one which is simple in construction and operation, highly practical, efficient and thoroughly 45 trustworthy and reliable, and which at the same time well illustrates the principles of my invention.

Figure 1 is a side elevation, partly broken away, showing this preferred form of my 50 invention.

Figs. 2, 3 and 4 are side elevations, partly sectioned, showing some of the parts of Fig. 1 in different positions assumed during operation.

Fig. 5 is a bottom plan view of a portion 55 of the structure seen in Fig. 1.

Fig. 6 is a top plan view and Fig. 7 a side elevation of the latch actuator.

Fig. 8 is a top plan view and Fig. 9 is a side elevation of the main lock or latch. 60

Fig. 10 is a side elevation and Fig. 11 an end elevation, of the auxiliary latch or lock.

In various lines of electric activity, it is desirable to provide a switch which is normally closed against spring tension, as 65 in the case of circuit breakers, or is subject to electromagnetic stresses tending to open it or which for some other reason must be locked in closed position to protect the circuit or circuits controlled by it, and 70 which is subject to such jolts, jars or shocks that the locking mechanism must be protected against movement causing premature release.

Since such movements may be due to a 75 single blow or to a series of blows in any direction, provision must be made to automatically reset the latch mechanism immediately, in case of any partial movement so as to protect the locking mechanism fully. 80

Referring to the drawing, 12 is a base or switchboard upon which are secured the main fixed contacts 13 and 13' adapted to be engaged and bridged by the movable laminated contact member 14 and thereby 85 close the circuit to be protected by the circuit breaker. The member 14 is secured at 14' to an arm 15 pivoted at 16 upon a fixed bracket or housing 17.

The switch operating arm 18 is pivoted at 90 19 in a fixed bracket, shown as the same bracket, and is connected to actuate the arm 15 by a toggle lever 20 and a toggle link 21. Of these, 20 is rigid with the operating arm 18 and 21 is pivoted to the arm 20 at 95 22 and to the arm 15 at 23.

In the position shown, the toggle mechanism represented by lever 20 and link 21 is slightly under-traveled, *i. e.*, it is not thrown quite far enough for the center of the pivot 100 at 22 to reach a line joining the centers of pivots 19 and 23. In this under-traveled position, the parts are given a normal tendency to open by a tension spring 24 which is secured at one end 25, to the arm 15 and 105 at the other end to the operating arm 18, as at 26.

At a suitable position to coöperate with

locking, latching and releasing mechanisms, hereinafter described, the operating arm carries a locking member in the form of a bolt or bar 27 which is shown here as comprising the transversely extending end of a strap 29. This strap and a strip 28 are secured to the operating arm conveniently by rivets 30. The strip 28 projects to limit the closing stroke of the operating lever by engagement of its end 31 with some fixed surface 32 such as the edge of bracket 17.

The locking mechanism, as shown, coöperating with the bar 27, comprises two parts, an arm or carrier 33 for a stop 34, 15 constituting the main lock or latch, and a catch-arm 35 presenting a catch surface 36, and constituting the auxiliary lock or latch. The stop-supporting arm or carrier 33 is pivoted at 37 to a fixed support, shown as bracket 17, and the catch arm 35 is pivoted 20 upon the carrier 33, at some such point as 38.

The stop-supporting arm 33 is conveniently formed as a frame, having two side walls 39 and 40 between which the stop 34 is placed, the stop being, for example, a roller mounted in the frame upon pivot 43.

The relation between the arc of movement of the bar 27 about the operating arm pivot 30 point 19 and of the stop 34 about the pivot at 37 is such that the stop normally lies directly in the line of movement of the bar in its arc of release movement indicated at 41; and the relation is further such that the contact between roller 34 and bar 27 lies substantially in a line passing through the centers of pivots 37 and 43.

The bar 27 may be slightly canted counter clockwise with respect to a line joining the 40 center of pivot 19 and the contact face of the bar, as shown, so that the tendency of the strain upon the operating arm 18 shall be to seat the stop more firmly in locking position, or it may be turned slightly in a 45 clockwise position, with respect to that shown, where the design is regarded as sufficiently safe to justify this change for the purpose of facilitating release of the stop from engagement with the bar.

50 In either event the face 42 of the bar should not depart far from a position of tangency to arc drawn through it about centers in the center of pivot 37.

For convenience in construction and to 55 make it more accessible for release tripping the pivot 37 for the carrier 33 is placed on that side of bar 27 toward the switch base 12; and the movement of the stop 34 is most desirably upward from its inactive to its 60 operative position.

The stop-carrier 33 is apertured at 37' for pivot 37 and at 38' for pivot 38 and the catch arm 35 is apertured at 38'' for pivot 38 and at 44 to receive one end of a

spring 45 whose other end is secured at a 65 fixed point 44'.

The relation between 38, 44 and 44' is such that, in the position shown in Fig. 1, the aperture 44 lies to the left of a line joining 38 and 44' and the spring is under tension, 70 holding the carrier 33 up and forcing the arm 35 in a clockwise direction on its pivot 38. This makes it possible to use the face 36 as a latch to maintain the arm 35 and, consequently, the carrier 33 and stop 34 in 75 raised position, by engaging this face with a relatively fixed surface.

The arm 35 thus performs the double function of lifting the carrier 33 and stop 34 to their operative positions and then holding 80 them there until suitable release mechanism is operated.

The latch face 36 is constantly and resiliently pressed in clockwise direction over the lock bar 27 so as to take up or regain any 85 counterclockwise movements which may have taken place due to jar and to correct and offset any tendency to cumulative releasing effect from repeated shocks.

The circuit breaker shown is provided 90 with the usual solenoidal coil 46, by which, when an excessive amount of current passes through the coil, the armature 47 is lifted. The core 47 may be adjusted, as usual, by means of a screw 48, locked by nut 49, to 95 respond to different magnitudes of current.

Movable with the core 47 is the head 50 which, upon upward attraction of the core, 100 strikes the under side of finger 52, of tripping structure 51, the finger 52 being mounted upon shaft 54, having bearings 55, and upon the other end of the shaft 54, displaced laterally from finger 52, is the finger 53, which partakes of counterclockwise movement with finger 52, a stop 56 limiting the 105 clockwise movement of both fingers 52 and 53. Manual operation of the device is provided by a knob 57 upon a plate 58 beneath the head 50 and, like the latter, movable upon the sides 59, 60 as guides. 110

The finger 53 lies under and communicates upward movement to a tail 61 of the latch actuator or trip 62. The latch actuator 62 is mounted between the sides 39, 40 of carrier 33 and is pivoted about the same 115 center 37 as that about which the stop carrier turns so that with movement of tail 61 of the latch actuator an extension 63 thereon is turned in a clockwise direction. The nose 64 upon this extension engages a shoulder 65 upon the auxiliary latch arm 35, turning this arm in a counterclockwise direction against the tension of spring 45 and releasing the hold of the nose or overhang 36 of the latch arm upon the bar 27. 120

Whereas, from the standpoints of the locking and latching mechanisms the roller-supporting member 33 is properly called a 125

stop carrier and the member 35 is properly called a latch arm, when these parts are considered from the standpoint of the tripping mechanism, as part of the tripping train, 5 they may be properly considered as main and auxiliary triggers or latches.

Considered from this standpoint, counter-clockwise movement of the auxiliary trigger latch 35 under the blow from the armature 10 47, through the latch actuator, proceeds without affecting the main trigger or latch 33 until the heel 66 of the auxiliary trigger 35 strikes the bottom 67 of the main trigger 33; at which time the blow is communicated 15 to the main trigger 33 and causes clockwise movement of the main trigger, withdrawing the stop (roller) 34 from the path of movement of the bar 27 upon operating arm 18. As soon as this occurs, the tendency of the 20 operating arm to move in a counterclockwise direction under the influence of spring 24, results in opening the switch.

Several positions of the parts which need to be considered are shown in Figs. 1, 2, 3 25 and 4. In Fig. 1 and in the dotted position in Fig. 2, the latch arm 35 is shown engaging the bar 27 and holding the stop carrier in raised position so that the stop 34 prevents release movement of the bar 27 along 30 its normal path of movement in the direction of the arrow and outlined by arc 41, the auxiliary latch preventing release of the main latch in response to shocks or jars.

When the latch actuator 62 has begun to 35 lift, its nose 64 engages the shoulder 65, turning the latch arm, now considered as an auxiliary trigger, and releasing its face 36 from the bar 27.

As the spring 45 is under tension, there 40 is no tendency to lower the stop carrier or the stop until the heel 66 of the auxiliary trigger strikes the bottom 67 of the stop carrier, now considered as a main trigger. This position is shown in full lines in Fig. 2.

Continued movement of the latch actuator 45 62 now causes clockwise movement of the stop carrier (main trigger) about the pivot 37 causing the stop 34 to pass below the lower arc of movement 41 of the bar 27 and 50 the spring 24 immediately throws the operating arm 18 and opens the switch. An intermediate position of the parts during this switch opening movement is shown in Fig. 3 where the stop has been moved considerably out of the path of movement of the bar 27 and the bar has moved to the right through part of the switch opening movement of the arm.

As soon as the force of the armature blow 60 is expended, the trigger parts come back to some such position relative to each other as that shown in Fig. 4 (intended to explain the resetting) where the spring 45 comes to rest with the fastening at 44 in a direct line 65 between the fastening at 44' and the pivot

38. Resetting movement of the switch operating arm requires that the bar 27 during its resetting movement in the direction of the arrow in Fig. 4 shall engage the stop 34 above its center line, so that the stop and its 70 carrier may be moved down sufficiently to permit the bar 27 to pass over it. At about the same time the bar 27 engages the latch arm 35 and forces it back. In the meantime the tension of spring 45 upon the latch arm, 75 communicated to the stop carrier, causes the stop carrier to rise coincidently with the counter-clockwise movement of the latch arm 35 caused by pressure of the bar 27 against the latter. As a result, the stop 34 80 is lifted as soon as the bar 27 has passed it sufficiently to permit this lifting and, finally, the lifting of the stop and the swinging of the latch arm bring the latch face 36 above the bar 27 and the spring 45 causes it to snap 85 over the latch bar, as shown in Fig. 1.

I claim—

1. In switch-locking mechanism, a movable contact member, an operating arm, in combination with means for blocking the release movement of the operating arm, movable in a direction across the path of the adjacent portion of the arm, and pivoted means carried by the first means for latching the latter in position. 90

2. In switch-locking mechanism, a movable contact member, an operating arm, in combination with a pivoted trigger movable into the path of release movement of the operating arm and receiving strain thereon 100 in line with its pivot point, and an auxiliary trigger pivoted to and retaining the main trigger in operative position.

3. In switch-locking mechanism, a movable contact member, an operating arm, in 105 combination with a main pivoted trigger adapted normally to lie in the line of release movement of the operating arm, means carried by the main trigger for retaining it in this position, and common spring means for 110 normally holding the trigger and auxiliary means in operative position.

4. In switch-locking mechanism, a movable contact member, an operating arm, a main trigger pivoted near one end and having a part adapted to swing into the path of release movement of the operating arm and to receive strain in line with its pivot point, a latch pivoted to the main trigger between the point of engagement of the operating arm and the pivot point, means for raising the main trigger and holding the latch in position, and a release trip for the latch engaging it to release the latch and to 115 throw the main trigger. 120

5. In locking mechanism for switches, a movable switch contact member, an operating arm, and a locking bar carried by the operating arm and having a path of release movement, in combination with a pivoted 130

- 4
- trigger adapted to enter said path to hold the locking bar in position, a pivoted latch carried by the trigger adapted to engage the locking bar to retain the trigger in position, and release means for operating the latch first and the trigger subsequently.
6. In locking mechanism for switches, a movable switch contact member, an operating arm, and a locking bar carried by the operating arm and having a path of release movement, in combination with a pivoted trigger, a roller carried by the trigger adapted to enter said path to engage the locking bar and retain the operating arm in switch-closing position, a latch carried by the trigger and engaging it to swing the trigger during release movement, spring means for setting the latch, and a trip for the latch and trigger.
7. In switch-locking mechanism, a movable contact member, an operating arm, a main trigger pivoted near one end and having a part adapted to swing into the path of release movement of the operating arm and to receive strain in line with its pivot point, a spring-supported latch on the trigger normally holding it in locking position and engaging it in release movement of the latch, and tripping means for the latch communicating with the trigger through the latch.
8. In a locking mechanism for automatic switches, a movable switch contact member, a switch-operating lever, and a locking bar thereon adapted to move in a curved path in combination with a swinging lock for the bar adapted to move into the path of movement of the bar, and a latch for the lock adapted to extend above the bar and engage it.
9. In switch-locking mechanism, a movable switch contact member and an operating lever having a bar thereon adapted to move in a curved path, in combination with a swinging lock movable into the path of movement of the bar and receiving strain therefrom in line with the point of support of the lock, and a swinging latch for the lock, swinging initially in the opposite direction and subsequently swinging with the lock.
10. In switch-locking mechanism, a movable switch contact member and an operating lever, in combination with an upwardly swinging lock engaging the operating lever, and a latch holding the swinging lock in lifted position and having initial lateral engaging and release movement.
11. In switch-locking mechanism, a movable switch contact member and an operating lever having a locking member connected therewith, in combination with a locking device movable into the path of release movement of the locking member, and a latch supported on the locking device and spring-raised to hold the locking device in locking position and the latch in latched position.
12. The combination with a movable member of an electric switch, of a main lock therefor comprising a pivoted member, a roller pivoted thereon and engaging said switch member to restrain the same in normal position, and means for preventing actuation of said main lock by shock or jar comprising an auxiliary latch pivoted on said pivoted member and engaging said switch member.
13. The combination with a movable member of a switch, of a main latch for restraining the same in normal position, and means for locking said main latch comprising an auxiliary latch pivoted on said main latch.
14. In locking mechanism for switches, a movable switch contact member, an operating arm, and a locking bar carried by the operating arm and having a path of release movement, in combination with a pivoted locking trigger movable into the path of movement of the locking bar, a latch pivoted to the trigger, and a spring fixed at one end and secured to the latch at the other end out of the line joining its fixed end and the latch pivot to lift the trigger through the latch and to throw the latch laterally to engaging position.
15. In locking mechanism for switches, a movable switch contact member, an operating arm, and a locking bar carried by the operating arm and having a path of release movement, in combination with a main locking trigger movable into the path of release movement of the locking bar, an auxiliary trigger adapted to latch the locking trigger in said position and to throw the main trigger, and a trip adapted to release the auxiliary trigger and through it the main trigger.
16. In locking mechanism for switches, a movable switch contact member, an operating arm, and a locking bar carried by the operating arm and having a path of release movement, in combination with a pivoted main trigger adapted to move into the path of release movement of the locking bar, an auxiliary trigger mounted thereon, means for maintaining the main and auxiliary triggers in locking position, a trip pivoted at approximately the same point as the main trigger and adapted to release the auxiliary trigger, and automatic means for actuating the trip.
17. In locking mechanism for switches, a movable switch contact member, an operating arm, and a locking bar carried by the operating arm and having a path of release movement, in combination with a main trigger adapted to move into locking engagement in the path of release movement of the locking bar, an auxiliary trigger thereon acting as a latch to hold the main trigger.

- trigger in locking position and having a heel adapted for engagement with the main trigger, and an automatic trip for the auxiliary trigger moving the auxiliary trigger 5 first and through it the main trigger.
18. In locking mechanism for switches, a movable switch contact member, an operating arm, and a locking bar carried by the operating arm and having a path of release 10 movement, in combination with a main trigger adapted to swing into the path of movement of the locking bar, an auxiliary trigger adapted to swing upon the main trigger and to support it, spring means for holding the 15 auxiliary trigger in position, supporting also the main trigger, and automatic means for tripping the auxiliary trigger first and subsequently the main trigger through the auxiliary trigger.
- 20 19. In locking mechanism for switches, a movable switch contact member, an operating arm, and a locking bar carried by the operating arm and having a path of release movement, in combination with a main trigger 25 pivoted to swing into locking engagement with the locking bar of the operating arm, an auxiliary trigger pivoted to the main trigger and adapted to latch over a relatively fixed member in one direction of 30 movement and to engage the main trigger in the opposite direction of movement, and a spring normally holding the auxiliary trigger in latching position.
20. In locking mechanism for switches, a 35 movable switch contact member, an operating arm, and a locking bar carried by the operating arm and having a path of release movement, in combination with a main trigger pivoted to swing into locking engagement with the locking bar of the operating arm, an auxiliary trigger pivoted to the main trigger and adapted to latch over a relatively fixed member in one direction of 40 movement and to engage the main trigger in the opposite direction of movement, a spring normally holding the auxiliary trigger in latching position, and a trip engaging the auxiliary trigger to unlatch it and to subsequently release the main trigger.
- 45 21. In locking mechanism for switches, a movable switch contact member, an operating arm, and a locking bar carried by the operating arm and having a path of release movement, in combination with a main trigger 50 pivoted to swing into locking engagement with the locking bar of the operating arm, an auxiliary trigger pivoted to the main trigger and adapted to latch over a relatively fixed member in one direction of 55 movement and to engage the main trigger in the opposite direction of movement, a spring normally holding the auxiliary trigger in latching position, a trip engaging the auxiliary trigger to unlatch it and to subse- 60 quently release the main trigger, and current-actuated means for operating the trip.
22. In locking mechanism for switches, a movable switch contact, an operating arm, in combination with a channeled trigger adapted to swing into the path of movement of the operating arm and prevent its movement, a latch entering the channel and supporting the trigger in this position, a trip entering the channel and engaging the latch to release it, the latch subsequently engaging the trigger to move it out of its normal position, and current-operated means for actuating the trip.
23. Trigger mechanism for the operating arm of an automatic switch comprising a main trigger pivoted near one end and near the other end adapted to be engaged by the switch-operating arm, and an auxiliary trigger pivoted to said main trigger and acting as a latch.
24. The combination with a base, of a movable member of a switch carried thereby, and locking mechanism for said movable member comprising a locking member pivoted to said base, a roller carried by said locking member and engaging said movable switch member, and a latch carried by and movable with respect to said locking member.
25. Trigger mechanism for switch-operating arm retention comprising a main trigger adapted to be pivoted near one end, a roller carried thereby for retention of the operating arm, and a latch carried by the trigger, having initial release movement opposite in direction to the release movement of the trigger and subsequently engaging the main trigger to move it in an opposite direction.
26. Trigger mechanism for switch-operating arm retention comprising a trigger adapted to be pivoted at one end and having channel form, a roller mounted within the channel near the opposite end thereof and adapted to come within the path of movement of the operating arm, and a latch pivoted within the channel and adapted to lie generally over the roller for engagement with the operating arm.
27. Trigger mechanism for switch-operating arm retention comprising a trigger adapted to be pivoted at one end and having channel form, a roller mounted within the channel near the opposite end thereof and adapted to come within the path of movement of the operating arm, a latch pivoted to extend within the channel, and a trip for the latch pivoted at the pivot point of the trigger and adapted to engage the latch.
28. Trigger mechanism for switch-operating arm retention comprising a trigger adapted to be pivoted at one end and having channel form, a roller mounted within the

- channel near the opposite end thereof and adapted to come within the path of movement of the operating arm, and a latch pivoted within the channel, adapted to lie generally over the roller for engagement with the operating arm and in release movement to engage the bottom of the channel and actuate the trigger.
29. The combination with a base, of a movable switch member carried thereby, a main latch carried by said base and engaging said switch member, and means for restraining said main latch comprising an auxiliary latch pivoted on said main latch.
- 10 30. The combination with a base, of a movable switch member carried thereby, a main latch pivoted to said base and engaging said switch member, and means for restraining said main latch comprising an auxiliary latch pivoted on said main latch.
- 15 31. The combination with a base, of a movable switch member carried thereby, a main latch carried by said base and engaging said switch member, and an auxiliary latch pivoted on said main latch and engaging said switch member.
- 20 32. The combination with a base, of a movable switch member carried thereby, a main latch pivoted to said base and engaging said switch member, and an auxiliary latch pivoted on said main latch and engaging said switch member.
- 25 33. The combination with a movable member of an electric switch, of a main lock therefor comprising a pivoted member, a roller pivoted thereon and engaging said switch member to restrain the same in normal position, means for preventing actuation of said main lock by shock or jar comprising an auxiliary latch pivoted on said pivoted member and engaging said switch member, and a latch actuator for actuating said pivoted member through said auxiliary latch.
- 30 34. The combination with a movable member of a switch, of a main latch for restraining the same in normal position, means for locking said main latch comprising an auxiliary latch pivoted on said main latch, and a latch actuator for actuating said auxiliary latch and main latch in succession.
- 35 35. The combination with a base, of a movable member of a switch carried thereby, and locking mechanism for said movable member comprising a locking member pivoted to said base, a roller carried by said locking member and engaging said movable switch member, a latch carried by and movable with respect to said locking member, and a latch actuator for actuating said locking member through said latch.
- 40 36. The combination with a base, of a movable switch member carried thereby, a main latch carried by said base and engaging said switch member, means for restraining said main latch comprising an auxiliary latch pivoted on said main latch, and a latch actuator for actuating said auxiliary latch pivoted on said main latch.
- 45 37. The combination with a base, of a movable switch member carried thereby, a main latch pivoted to said base and engaging said switch member, means for locking said main latch comprising an auxiliary latch pivoted on said main latch, and a latch actuator for actuating said auxiliary latch through said auxiliary latch.
- 50 38. The combination with a base, of a movable switch member carried thereby, a main latch carried by said base and engaging said switch member, an auxiliary latch pivoted on said main latch and engaging said switch member, and a latch actuator for actuating said auxiliary latch and through it said main latch.
- 55 39. The combination with a base, of a movable switch member carried thereby, a main latch pivoted to said base and engaging said switch member, an auxiliary latch pivoted on said main latch and engaging said switch member, and a latch actuator for actuating said main latch through said auxiliary latch.
- 60 40. The combination with a movable member of an electric switch, of a main lock therefor comprising a pivoted member, a roller pivoted thereon and engaging said switch member to restrain the same in normal position, means for preventing actuation of said main lock by shock or jar comprising an auxiliary latch pivoted on said pivoted member and engaging said switch member, and a spring opposing release of said auxiliary latch and through it opposing release of said pivoted member.
- 65 41. The combination with a movable member of a switch, of a main latch for restraining the same in normal position, means for locking said main latch comprising an auxiliary latch pivoted on said main latch, and a spring attached to said auxiliary latch controlling the same and said main latch.
- 70 42. The combination with a base, of a movable member of a switch carried thereby, and locking mechanism for said movable member comprising a locking member pivoted to said base, a roller carried by said locking member and engaging said movable switch member, means for restraining said locking member comprising a latch carried by and movable with respect to said locking member, and a spring attached to said base and through said latch to said locking member.
- 75 43. The combination with a base, of a movable switch member carried thereby, a main latch carried by said base and engaging said switch member, means for locking said main latch in locking position comprising an auxiliary latch pivoted on said main latch.
- 80 44. The combination with a base, of a movable switch member carried thereby, a main latch carried by said base and engaging said switch member, means for locking said main latch in locking position comprising an auxiliary latch pivoted on said main latch.
- 85 45. The combination with a base, of a movable switch member carried thereby, a main latch carried by said base and engaging said switch member, means for locking said main latch in locking position comprising an auxiliary latch pivoted on said main latch.
- 90 46. The combination with a base, of a movable switch member carried thereby, a main latch carried by said base and engaging said switch member, means for locking said main latch in locking position comprising an auxiliary latch pivoted on said main latch.
- 95 47. The combination with a base, of a movable switch member carried thereby, a main latch carried by said base and engaging said switch member, means for locking said main latch in locking position comprising an auxiliary latch pivoted on said main latch.
- 100 48. The combination with a base, of a movable switch member carried thereby, a main latch carried by said base and engaging said switch member, means for locking said main latch in locking position comprising an auxiliary latch pivoted on said main latch.
- 105 49. The combination with a base, of a movable switch member carried thereby, a main latch carried by said base and engaging said switch member, means for locking said main latch in locking position comprising an auxiliary latch pivoted on said main latch.
- 110 50. The combination with a base, of a movable switch member carried thereby, a main latch carried by said base and engaging said switch member, means for locking said main latch in locking position comprising an auxiliary latch pivoted on said main latch.
- 115 51. The combination with a base, of a movable switch member carried thereby, a main latch carried by said base and engaging said switch member, means for locking said main latch in locking position comprising an auxiliary latch pivoted on said main latch.
- 120 52. The combination with a base, of a movable switch member carried thereby, a main latch carried by said base and engaging said switch member, means for locking said main latch in locking position comprising an auxiliary latch pivoted on said main latch.
- 125 53. The combination with a base, of a movable switch member carried thereby, a main latch carried by said base and engaging said switch member, means for locking said main latch in locking position comprising an auxiliary latch pivoted on said main latch.
- 130 54. The combination with a base, of a movable switch member carried thereby, a main latch carried by said base and engaging said switch member, means for locking said main latch in locking position comprising an auxiliary latch pivoted on said main latch.

main latch, and a spring attached to said base and to said auxiliary latch.

44. The combination with a movable member of a switch, of a main latch for restraining the same in normal position, means for locking said main latch comprising an auxiliary latch pivoted on said main latch, a latch actuator for actuating said auxiliary latch and main latch in succession, and a

10 spring opposing said actuator connected to said auxiliary latch.

45. The combination with a base, of a movable switch member carried thereby, a main latch pivoted to said base and engaging said switch member, an auxiliary latch pivoted on said main latch and engaging said switch member, a latch actuator for actuating said main latch through said auxiliary latch, and a spring opposing said

20 actuator connected to said base and to said main latch through said auxiliary latch.

46. The combination with a base, of a movable member of a switch carried thereby, a main latch carried by said base and engaging said switch member, means for locking said main latch comprising an auxiliary latch carried by and movable upon said main latch, and a spring connected to said main latch through said auxiliary latch.

25 47. The combination with a base, of a

movable member of a switch carried thereby, a main latch carried by said base and engaging said switch member, an auxiliary latch engaging a member other than said main latch and carried by and movable upon 35 said main latch, and a latch actuator for actuating said main latch through said auxiliary latch.

48. The combination with a base, of a movable member of a switch carried thereby, a main latch carried by said base and engaging said switch member, an auxiliary latch engaging a member other than said main latch and carried by and movable upon 40 said main latch, a latch actuator for actuating said main latch through said auxiliary latch, and a spring opposing said actuator 45 connected to said auxiliary latch and through it to said main latch.

49. The combination with a base, of a movable member of a switch carried thereby, a main latch carried on said base and engaging said switch member to restrain the same in normal position, and means for locking said main latch comprising an auxiliary latch engaging a member other than said main latch and carried by said main latch.

HENRY JOHN SCHMID.
